STABILIZATION OF OLEAGINOUS MATERIALS

Frank A. Norris, Minneapolis, Minn., assignor to
General Mills, Inc., a corporation of DelawareNo Drawing. Application December 1, 1944,
Serial No. 566,243

9 Claims. (Cl. 99—163)

1

The present invention relates to a process of stabilizing oleaginous materials against the development of rancidity, and to the resultant product. The invention is directed particularly to oleaginous materials composed of or containing animal fats or oils, such as oils, shortening, salad dressings, spreads, and the like.

The present invention involves a synergistic antioxidant effect resulting from the combined use of a plurality of substances. It has been found that combinations of certain antioxidants produce a resultant stability far in excess of the sum of the stabilities obtained by the use of the compounds singly.

It is therefore a primary object of the present invention to provide a process of stabilizing fatty or oleaginous materials against oxidation and the development of rancidity.

It is another object of the invention to provide products containing fats or oils which are stabilized against oxidation and the development of rancidity.

A further object of the invention is to provide a process of stabilizing fatty or oleaginous products of animal origin by means of antioxidants which exhibit synergistic effects.

These and other objects of the invention will be apparent from the following description of the invention with particular reference to specific examples which are to be understood as illustrative only and not as limiting the invention.

It has been found that a synergistic antioxidant effect is obtained by the conjoint use of caffeic acid and compounds containing the ene-diol group

such as l-ascorbic acid. While ascorbic acid, which is water-soluble, has been known to have antioxidant effect in aqueous media, it has not been particularly effective in fats, probably because of its extremely low solubility. Caffeic acid, on the other hand, has an appreciable antioxidant effect in fatty media. It has been found, however, that when these two compounds are used together, they exhibit a pronounced synergistic effect which give the oleaginous material in which they are incorporated a stability far in excess of that of the untreated material and far in excess of the sum of the individual stabilities contributed when each of these compounds is used alone.

2

This is demonstrated by the following table showing the effect of these antioxidants on prime steam lard.

5	Sample	"Swift" Stability Hours	Protective Factor
1	Prime Steam Lard.....	1	—
2	(1)+0.015% caffeic acid.....	48	48
3	Prime Steam Lard.....	2.5	—
4	(3)+0.03% p-amino-benzoic acid—less than.....	2.3	1
5	(3)+0.05% l-ascorbic acid—less than.....	11.5	4.6
6	Prime Steam Lard.....	3.8	—
7	(6)+0.03% p-amino-benzoic acid+0.05% l-ascorbic acid.....	32	8.5
8	(6)+0.03% p-amino-benzoic acid+0.05% l-ascorbic acid+0.015% caffeic acid.....	307.5	31

In place of l-ascorbic acid other compounds having the ene-diol groups such as reductone, dihydroxymaleic acid, analogues or isomers of ascorbic acid, such as isoascorbic acid, glucoascorbic acid, araboascorbic acid, etc., may be used.

The prime steam lard employed was the article available on the market, and it was used in these tests without any additional purification. Hydrogenation of this impure material results in a decided increase in stability. However, for the purpose of these tests, the material was not hydrogenated in view of the fact that even without hydrogenation the time required for some of the tests was prolonged for weeks because of the high stabilities. It will be apparent, therefore, that the process may be employed on other materials having originally higher or lower stabilities, in which case it may be desirable to reduce or increase the amount of antioxidant added.

Instead of the amounts of antioxidants shown above, it is possible to employ decidedly lower concentration where such a high stability is not necessary or desirable. The lower limit of antioxidant to be added appears to be dictated by the resultant stability desired. There does not appear to be any upper limit to the amount of antioxidant which may be employed. However, the cost of the antioxidant constituents usually dictates that they should not be employed in much greater concentration than 0.1 per cent.

In addition to its effect on the antioxidant properties of the product, p-amino-benzoic acid has decided preservative action and represses

microbiological growth. The common materials employed to inhibit oxidative rancidity have no effect on microbiological growth. Consequently yeast, molds, and the like, continue to grow and produce hydrolytic or other enzymic changes which result in rancidity. Thus, while the rancidity so produced is a distinct disadvantage in itself, the presence of large numbers of microorganisms is an even greater disadvantage in view of the possible ill effect on those who consume such a product.

It is apparent that these various objections of the prior art are overcome by the present invention in that it inhibits both oxidative rancidity and microbiological growth. Hydrolytic and enzymic rancidity are likewise inhibited in view of the inhibition of microbiological growth. Moreover, all of the substances are non-toxic and the p-amino-benzoic acid and l-ascorbic acid are recognized vitamins which perform additional functions when consumed.

It is also to be understood that the invention may be applied to animal oils or fats of any nature whether edible or not, all of which products are contemplated by the term "oleaginous material of animal origin" as used in the appended claims.

I claim as my invention:

1. A composition of matter comprising an oleaginous material of animal origin containing, and being stabilized against the development of rancidity by, not substantially in excess of one-tenth per cent of each of l-ascorbic acid, p-amino-benzoic acid, and caffeic acid.

2. A composition of matter comprising an oleaginous material of animal origin containing, and being stabilized against the development of rancidity by, not substantially in excess of .1 per cent of each of a compound containing an enediol group, p-amino-benzoic acid, and caffeic acid.

3. A process of stabilizing an oleaginous material of animal origin which comprises incorporating therein, not substantially in excess of one-tenth per cent of each of l-ascorbic acid, p-amino-benzoic acid, and caffeic acid.

4. A process of stabilizing an oleaginous material of animal origin which comprises incorporating therein, not substantially in excess of .1 per cent of each of a compound containing an ene-

diol group, p-amino-benzoic acid, and caffeic acid.

5. An edible shortening containing an oleaginous material of animal origin, and being stabilized against the development of rancidity by, not substantially in excess of .1 per cent of each of l-ascorbic acid, p-amino-benzoic acid, and caffeic acid.

10 6. A composition of matter comprising an oleaginous matter of animal origin containing, and being stabilized against the development of rancidity by, approximately 0.03% p-amino-benzoic acid, 0.05% of a compound containing an enediol group, and 0.015% caffeic acid.

15 7. A composition of matter comprising an oleaginous matter of animal origin containing, and being stabilized against the development of rancidity by, approximately 0.03% p-amino-benzoic acid, 0.05% of l-ascorbic acid, and 0.015% caffeic acid.

20 8. A process of stabilizing an oleaginous material of animal origin which comprises incorporating therein, approximately 0.03% p-amino-benzoic acid, 0.05% of a compound containing an ene-diol group, and 0.015% caffeic acid.

25 9. A process of stabilizing an oleaginous material of animal origin which comprises incorporating therein, approximately 0.03% p-amino-benzoic acid, 0.05% of l-ascorbic acid, and 0.015% caffeic acid.
